(57) **CLAIM**

The ornamental design for a hockey puck shaped frame for license plates and pictures, as shown and described.

DESCRIPTION

FIG. 1 is a front perspective view of a hockey puck shaped frame for license plates and pictures according to the present invention, showing the frame attached to a vehicle and holding a license plate.

FIG. 2 is another front perspective view thereof.

FIG. 3 is a front elevation view thereof.

FIG. 4 is another front perspective view thereof.

FIG. 5 is another front elevation view thereof.

FIG. 6 is an edge view thereof.

FIG. 7 is a rear elevation view thereof.

FIG. 8 is a front perspective view thereof, showing the frame mounted to a wall.

FIG. 9 is a front perspective view thereof, showing the frame supported by an easel; and,

FIG. 10 is an edge perspective view thereof, showing the frame placed on a table top.

The dotted lines in the drawings illustrate use environments of the design which form no part of the design claimed.

The dot-dash lines in the drawings illustrate boundaries of use environments of the design which form no part of the claimed design.

1 Claim, 4 Drawing Sheets
